CLAIM

We claim the ornamental design for a tray lid, as shown and described.

DESCRIPTION

FIG. 1 is a perspective view of a tray lid, showing our new design;

FIG. 2 is a top view thereof;

FIG. 3 is a bottom view thereof;

FIG. 4 is a first end view thereof, the second end view being a mirror image thereof; and,

FIG. 5 is a first side view thereof; the second side view being a mirror image thereof.
